UNITED STATES PATENT OFFICE.

DOWLING CLEMENTS MOREIS AND JOHN WILLIAM PALMER, OF CHATTANOOGA,
TENNESSEE.

PIPE AND NUT WRENCH.

Application filed May 31, 1923. Serial No. 642,585.

To all whom it may concern:

Be it known that we, DOWLING C. MORRIS and JOHN W. PALMER, citizens of the United States, residing at Chattanooga, in the 5 county of Hamilton and State of Tennessee, have invented a new and useful Pipe and Nut Wrench, of which the following is a specification.

The device forming the subject matter of 10 this application is a wrench, adapted to be used for turning either nuts or round objects, and the invention aims to provide a simple means whereby one jaw of the wrench may be shifted readily with respect 15 to the other jaw thereof and be held in adjusted positions.

It is within the province of the disclosure 20 to improve generally and to enhance the utility of devices of that type to which the invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:—

Figure 1 shows in side elevation, a wrench constructed in accordance with the invention; Figure 2 is a plan; Figure 3 is a cross 35 section; Figure 4 is a perspective view showing the latch; Figure 5 is an elevation showing a modification, parts being broken away.

The numeral 1 marks a shank carrying a 40 fixed jaw 2. A rider 3 in the form of a bar, is mounted for reciprocation on the shank 1, longitudinally thereof, and has a jaw 5 cooperating with the jaw 2. The shank 1 is surrounded by a U-shaped keeper 5 held by securing elements 6 on the rider 3. 45 One side portion of the keeper 5 is equipped with an opening 7. Bearings 8 are formed on the said side portion of the keeper 5, and are located at the ends of the openings 7. A suspension pin 9 is mounted in the bearings 8. A plate-like latch 10 is provided 50 and is of such a size as to substantially fill

the opening 7 in the side of the keeper 5. Along one edge, the latch 10 is equipped with a socket 11 wherein the suspension pin 9 is received. The latch pin, therefore, is 55 mounted for swinging movement on the keeper 5. Along one edge, the latch pin has inwardly extended projections 12 adapted to engage with seats 14 formed in the inner edge of the shank 1. Intermediate the seats 14, the latch 10 is bulged outwardly at its edge to form a finger piece 15.

Through the instrumentality of the finger piece 15 the latch 10 may be swung inwardly and outwardly, thereby bringing the projections 12 on the latch into and out of engagement with the seats 14 on the shank 1 of the wrench. It is obvious that, through the instrumentality of the mechanism above pointed out, the rider 3 may be held in any position to which it may have been adjusted, longitudinally of the shank 1.

If desired, the rear end of the shank 1 may be curved, as at 16, so as to overhang the end of the rider 3, the curved portion 16 75 of the shank, and the end of the rider 3 being equipped with cooperating teeth 17, enabling the device to be used as a pipe wrench, the parts 2 and 4 cooperating to 80 form a nut wrench.

As a general statement, the ends of the parts 1 and 3 may be fashioned in any desired way, depending upon the character of the work to be done. Thus, in Figure 5, the shank is denoted by the numeral 18 and 85 the rider by the numeral 19, the parts 18 and 19 having, each, oppositely inclined jaws 20, provided with internal teeth 21, parts not shown in Figure 5 being constructed as hereinbefore set forth in connection with 90 that form of the invention which is depicted in Figure 1.

What is claimed is:—

In a wrench, a shank, a rider, the shank and the rider being provided with cooperating jaws, a keeper secured to the rider and receiving the shank slidably, thereby to mount the rider on the shank for reciprocation longitudinally of the shank, one side portion of the keeper being provided with 95 an opening located entirely within said side portion of the keeper, and a latch hinged to 100

the keeper and adapted to fit in the opening, the free end of the latch being outwardly distorted beyond said side portion of the keeper, to facilitate the manipulation of the latch, the latch being provided upon each side of its distorted portion, with projections, and the inner edge of the shank being provided with seats wherewith the projec-

tions cooperate to hold the rider in adjusted positions longitudinally of the shank.

In testimony that we claim the foregoing as our own, we have hereto affixed our signatures.

DOWLING CLEMENTS MORRIS.
JOHN WILLIAM PALMER.
